TOY HORSE

Edward McMellon, North Harrow, England

Application June 11, 1947, Serial No. 753,908
In Great Britain May 23, 1946

5 Claims. (Cl. 280—1.20)

1

This invention relates to toy horses and the like, its object being to provide a simple construction which enables the toy to be propelled by a movement closely resembling actual horse-riding and whilst intended primarily for the use of children, it can obviously be made of a size suitable for the use of adults in gymnasiums.

A simple embodiment of the invention is shown in the accompanying drawing, wherein—

Fig. 1 is a side elevation;

Fig. 2 is a rear end view of Fig. 1;

Fig. 3 is a plan of the rocking bar of Fig. 1 shown to a larger scale.

According to the present invention, I provide a toy horse mounted on wheels or castors and having an arcuate or radiused movement effected by the rider to propel the device. For this purpose the toy comprises a frame carried on wheels, and on which is mounted a rocking bar bearing a seat.

To one end of the rocking bar is attached an arm or the like for stirrups whilst the other end of the rocking bar is coupled to the axle for the rear wheels so that a person seated on the saddle and exerting pressure on the stirrups with an up and down movement of the body as in actual horse riding, will not only obtain the same exercise but will propel the toy by such movements. The rocking bar is coupled to the axle preferably by means of a crank eccentrically pivoted to a sprocket wheel or the like which is itself coupled by a chain to a similar sprocket wheel on the rear axle.

A head for the toy is disposed at the forward end of the rocking bar and is supported on a spindle which is carried in a bearing sleeve, the rotation of said spindle in the sleeve being limited for instance by a pin on the spindle coacting with a notch or notches in the sleeve. At its lower end, remote from the steering head, the said spindle is bent or curved and engaged with a fork arranged at the upper end of another spindle carrying a steerable front wheel, whereby steering of the latter may be effected by movement of the steering head, no matter what the position of the rocking bar is with respect to the frame.

In the example illustrated, a frame 1 mounted on wheels 2 has inclined forward and rear members 1a and 1b respectively an upper cross-bracing strut 3, a lower cross-bracing strut 4, and outwardly splayed rear ends 5 which latter carry a linear axle 6 for the rear wheels. At its upper part, the frame 1 has a rocking bar 7 pivoted at a point 8. The rocking bar comprises two

2

parallel members 9 rigidly attached together by a plurality of distance pieces 10, one of which at the forward end of the bar forms a rigid mounting for a sleeve 11. Bolts 12 are provided on two other distance pieces and serve for the attachment of the body 13 (shown in broken line for clarity). Towards its rear end, the rocking bar 7 carries a crank pin 14 on which is pivoted a connecting rod 15 serving to couple the rocking bar to a sprocket 16 having a chain 16a which latter also passes round a similar sprocket 16b on the rear axle.

The rocking bar also carries, towards its rear end, a seat 17 and towards its front end a pair of stirrups 18. The sleeve 11 at the front end of the rocking bar serves as a bearing for a steering spindle 19 carrying a head 19a (shown in broken line for clarity) the movement of which with respect to the sleeve is limited by means of a pin 20 on the spindle movable in a slot 21 in the sleeve. The lower end of the spindle 19 has a crank 22 which bears at its end a tongue 23. The tongue engages with a forked bell crank 24 at the upper end of a steering column 25 which is pivoted at points 26 and 27 at the front of the frame. By this means, no matter what the position of the rocking bar is about its pivot point 8 the steering spindle 19 engages with the steering column 25 for any movement of the steering spindle about the axis of the sleeve 11. A steerable front wheel is attached at the lower end of the steering column.

I claim:

1. A toy horse, a frame therefor comprising inclined forward and rear members, upper and lower cross-bracing struts therefor, outwardly splayed ends on said inclined rear frame member, a linear rear axle carrying rear wheels supported in the said splayed ends of the rear frame member, a pivotal bearing at the top of the frame for a rocking bar disposed above said frame, stirrups and a seat carried by said rocking bar respectively forward of and rearwardly of said pivot, driving mechanism between the rocking bar and the said rear axle, a steering column carried by said frame, a steering spindle carried by the said rocking bar to actuate said steering column, and a bearing sleeve for the steering spindle at the front end of the rocking bar.
2. In a toy horse as claimed in claim 1, means to limit the turning of the steering spindle comprising a pin on said steering spindle and a notch in the said bearing sleeve to receive said pin.
3. In a toy horse as claimed in claim 1, a crank at the lower end of the steering spindle, a tongue

on the end of said crank, and a forked bell crank at the upper end of the steering column to engage with the tongue, whereby the steering spindle and column are engaged with each other when the steering spindle is rotated about the longitudinal axis of the bearing sleeve.

4. In a toy horse as claimed in claim 1, the rocking bar consisting of two parallel members rigidly attached together by a plurality of distance pieces, a rigid mounting formed by one of the said distance pieces for the sleeve disposed at the forward end of the rocking bar, bolts provided on two other of said distance pieces for the attachment of the body, a crank pin mounted on still another distance piece at the rear end of the rocking bar, a connecting rod pivoted on said crank pin, and sprocket and chain means coupling said connecting rod to the rear axle.

5. A toy horse, a frame therefor comprising inclined forward and rear frame members, upper and lower cross-bracing struts therefor, outwardly splayed ends on said rear frame member, a linear axle carrying rear wheels supported in said splayed ends of the rear frame member, a pivotal bearing at the top of the frame for a rocking bar disposed above said frame, stirrups and a seat carried by said rocking bar respectively forward and rearward of said pivot, a connecting

5 rod coupled towards the rear end of the rocking bar, a sprocket wheel mounted on the inclined rear frame member and receiving eccentrically one end of the said connecting rod, another sprocket wheel carried on the rear axle and a sprocket chain passing round both of the said sprocket wheels to form a coupling therefor.
